UNITED STATES PATENT OFFICE.

BYRON BENJAMIN GOLDSMITH, OF NEW YORK, N. Y.

ERASER.

SPECIFICATION forming part of Letters Patent No. 605,163, dated June 7, 1898.

Application filed May 18, 1895. Serial No. 549,768. (No model.)

To all whom it may concern:

Be it known that I, BYRON BENJAMIN GOLDSMITH, a citizen of the United States, and a resident of New York, in the county and State of New York, have invented certain new and useful Improvements in Erasers, of which the following is a specification.

My invention has reference to improvements in pencil and ink erasers adapted for general and independent use, but more particularly useful in connection with lead-pencils; and its object is to provide an eraser whereby the use of glue or cement for holding the erasing material (generally rubber) in its support is avoided, whereby the erasing material is utilized to greater advantage and at the same time is so held that accidental extraction from the holder is prevented.

An eraser constructed in accordance with this invention is composed of a sleeve or ferrule having one end contracted in any manner, but preferably so as to be tapering or conical, and having a block of erasing material, provided with a head or enlargement, confined in the contracted end of the ferrule in such manner that the erasing-block is exposed for use, but cannot be removed through the front end of the ferrule, and that it can only be removed through the rear end, through which it was introduced, by the application of considerable force.

If the eraser is intended for independent use, the accidental extraction of the erasing-block through the rear end of the ferrule is prevented by an interior ledge within the ferrule end or by a block of wood or similar material. If the eraser is to be used as an adjunct to a lead-pencil, then the lead-pencil itself may perform the function of such block or ledge. All this will more fully appear from the following detail description, taken in connection with the accompanying drawings, which form a part of this specification, and in which—

Figure 1 is an enlarged longitudinal section, partly in elevation, of the improved eraser as applied to a lead-pencil. Fig. 2 is a perspective view of another form of the improved eraser when used as an adjunct to a lead-pencil; and Fig. 3 is an enlarged longitudinal section, partly in elevation, of a third form of the improvement. Fig. 4 is a

perspective view of the improved eraser combined with a brush. Fig. 5 is a longitudinal section thereof. Fig. 6 is a longitudinal section of a combined pencil and ink eraser made in accordance with the invention. Fig. 7 is a side view of the improved eraser adapted to serve as a point-protector for a lead-pencil. Fig. 8 is a plan view, with parts broken away, of my improved eraser adapted for independent use. Fig. 9 is a section of the same on the line $\alpha\alpha$ of Fig. 8, and Fig. 10 is a view of another form of independent eraser.

Like numerals of reference indicate like parts.

Referring now particularly to Fig. 1, the sleeve or ferrule 1, which constitutes the holder for the erasing-block 2, is contracted at its forward end 3, and immediately in the rear of the taper thus formed there is in the outer surface of the sleeve a depression or groove 4, passing all around the sleeve and forming in the interior a corresponding bead or ledge 5. The erasing-block 2 is of practically uniform thickness throughout the greater portion of its length, but has at its rear end a tapering head 6, conforming in size and shape to the taper 3 of the forward end of the sleeve.

The erasing-block is inserted into the holder-sleeve through the contracted open end of the same, with the uniform portion of the block toward the tapering end of the sleeve, through which end that uniform portion of the block 85 is projected. Then the head 6 is forced past the ledge 5, and the block is thus confined between the taper 3 of the sleeve and the ledge 5, so that it can neither be extracted from the sleeve forwardly nor pushed back 90 by the pressure ordinarily exerted in the use of the eraser. If the tapering head of the erasing-block is of the proper size, it will be so tightly held between the nozzle of the sleeve and the ledge behind the same that it cannot 95 be loosened by the bending and shaking to which it is subjected in the ordinary manipulation of the device. It will be seen that only a very small portion of the eraser-block is confined in the sleeve and that by far the greater portion of it projects beyond the same in position for use. Thus a great saving in erasing material is secured as compared with erasers heretofore made, where the greater

portion of the erasing material was held in the sleeve in order to prevent as much as possible its pulling out or loosening in the holder; but notwithstanding the great waste of erasing material necessitated by these old constructions the erasing-block would frequently become loose in the holder and eventually drop out.

In Fig. 1 the eraser is shown as an attachment to a lead-pencil 7, over which the sleeve 1 is slipped as a ferrule, and while this special use of the improved eraser offers particular advantages I am by no means confined to that use, since the eraser may be used independently of lead-pencils, as will be readily understood and as will more particularly appear farther on.

In Fig. 1 the erasing-block is supposed to be cylindrical; but it may be prismatic, as shown in the perspective view in Fig. 2, in which case the nozzle will have flat pyramidal faces 3', as indicated.

When the improved eraser is used as an attachment to lead-pencils, its construction may be slightly simplified, as shown in Fig. 3. In this case the groove 4 and corresponding ledge 5 may be omitted from the sleeve, since the body of the pencil 7 would assume the function of the ledge.

As an independent structure the whole body of the eraser may be prismatic, as shown in Figs. 4, 5, and 6. Figs. 4 and 5 illustrate an eraser of this kind combined with a brush. The eraser proper is shown exactly as in the preceding figures of drawings, and particularly as in Fig. 2, except that the sleeve 1 is here shown prismatic; but in all other respects the construction is the same. The brush-holder is a simple prismatic tube with slots 9 in its sides, so that it may be easily slipped into and out of the sleeve 1. The brush 10 for removing the abraded particles of paper and erasing material is glued or otherwise secured in the tube 8.

In Fig. 6 there are shown two erasers with their sleeves 11 telescoping; but otherwise the construction is the same as that shown in Figs. 4 and 5. Ordinarily one of the erasing-blocks 2 will be soft for erasing pencil-marks and the other 2' will be hard and somewhat gritty for erasing ink-marks.

In Fig. 7 the sleeve 1 is shown composed of two semicylindrical parts 1' and 1'', held together by a ring 11, but in other respects is similar to the form shown in Fig. 1. This form of the eraser-holder is so constructed that it may be slipped upon the butt-end of a pencil, but grips the same with sufficient friction to remain in place when the eraser is in use. It may also be removed from the butt-end of the pencil and slipped onto the sharpened end thereof, and thereby act as a point-protector.

In Figs. 8, 9, and 10 there is shown an independent eraser having three equidistant radial blocks 2 of erasing material projecting from a flat hexagonal case 12. Three side

walls of the case 12 are cut away, and the remaining sides 13 form with the same three equidistant tapering nozzles for the erasing-blocks 2. The case 12 is formed of two like parts held together by a rivet or bolt 14, as indicated in Fig. 9.

In the form shown in Figs. 8 and 9 the erasing-blocks 2 are held against rearward movement by a hexagonal block 15 of wood or other material within the case, and in the form shown in Fig. 10 the grooves 4, forming corresponding inwardly-projecting ledges, perform the same function as the block 15.

It will be observed that the forms of independent eraser shown in Figs. 8, 9, and 10 are in effect but a multiplication of the form shown in Fig. 7.

It will be readily understood that numerous other variations of the details of construction may be made without departing from my invention, and I am therefore not limited to the identical features herein shown and described.

Having now fully described my invention, I claim and desire to secure by Letters Patent—

1. A pencil or ink eraser composed of a holder having a tapering, contracted nozzle and a block of erasing material with a body portion of such size as to pass freely through the mouth of the nozzle, and a head or enlargement conforming in shape to the tapered nozzle and too large to pass through the mouth thereof, substantially as described.

2. A pencil or ink eraser composed of a holder having a contracted nozzle and an inwardly-projecting ledge behind the same, and a block of erasing material having a body portion of such size as to pass freely through the mouth of the nozzle and formed with a head conforming to the nozzle and too large to pass through the mouth thereof, and engaging the ledge, substantially as described.

3. A pencil or ink eraser composed of a holder consisting of two pieces of such shape that, when secured together, they conspire to form a contracted nozzle, and a block of erasing material formed with a body portion free to pass through the nozzle and a head or enlargement conforming to the nozzle too large to pass through the mouth thereof, substantially as described.

4. A pencil or ink eraser composed of a holder consisting of two pieces of such shape that, when placed together, they conspire to form a number of contracted nozzles, and blocks of erasing material, one for each nozzle, each block being formed with a body portion of such size as to freely pass through the nozzle and a head or enlargement conforming to the nozzle and too large to pass through the mouth thereof, substantially as described.

5. A pencil or ink eraser, composed of a holder consisting of two pieces of such shape that, when placed together, they conspire to form a number of contracted nozzles each with an inwardly-projecting ledge behind it,

and blocks of erasing material, one for each nozzle, each block being formed with a body portion of such size as to freely pass through the nozzle and a head or enlargement conforming to the nozzle, too large to pass through the mouth thereof, and engaging the ledge, substantially as described.

6. A pencil or ink eraser composed of a holder having a contracted nozzle, a block of erasing material having a body portion of such size as to pass freely through the mouth of the nozzle and a head conforming to the nozzle,

zle and too large to pass through the mouth thereof, and means for preventing rearward movement of the erasing block in the nozzle, substantially as described.

In testimony whereof I have signed my name to this specification in the presence of two subscribing witnesses.

BYRON BENJAMIN GOLDSMITH.
